(57) **CLAIM**

The ornamental design for a work surface assembly, as shown and described.

DESCRIPTION

In a preferred embodiment, the nature of this product is a worksurface assembly that is part of a modular office furniture system.

FIG. 1 is a top, front, left perspective view of a work surface assembly embodying our new design;

FIG. 2 is a front elevational view thereof, the rear elevational view being identical to the front elevational view;

FIG. 3 is a right side elevational view thereof, the left side elevational view being identical to the right side elevational view;

FIG. 4 is a top plan view thereof; and,

FIG. 5 is a bottom plan view thereof.

The broken line representations of a work surface in FIGS. 1-5, of a vertical panel in FIGS. 1-3, of vertical work surface support structure in FIGS. 1-5, of vertical panel support structure in FIGS. 1-3, and of work surface support structure in FIG. 5 are for environmental purposes only and form no part of the claimed design.
